SUPPORT FOR LIQUID TREATING VESSELS

Ralph M. Parsons, Chicago, Ill., assignor to The Ralph M. Parsons Company, Chicago, Ill., a corporation of Delaware

Original application March 2, 1935, Serial No. 8,989, now Patent No. 2,079,333, dated May 4, 1937. Divided and this application July 20, 1936, Serial No. 91,470

1 Claim. (Cl. 248—146)

This invention relates to a support for a liquid treating vessel and more particularly to a support for a heavy vessel of the type used in oil cracking plants.

5 This application is a division of my copending application, Serial No. 8,989, filed March 2, 1935, for Liquid treating vessel and support therefor which application became Patent 2,079,333, dated May 4, 1937.

10 An object of the invention is to provide a simple, rigid, dependable and economical support of the above type.

Another object is to provide a support which may be attached to the vessel at the factory and which facilitates the erection of the vessel in the field.

15 Various other objects and advantages will be apparent as the nature of the invention is more fully disclosed.

20 The invention is capable of various uses and will be understood from the following description, taken in connection with the accompanying drawing in which one embodiment thereof is set forth. In the drawing,

25 Fig. 1 is a vertical section of a portion of a flash chamber showing the supporting legs attached thereto.

Fig. 2 is a broken side elevation thereof.

Fig. 3 is a horizontal section taken on the line 30 3—3 of Fig. 1, and

Figs. 4 and 5 are partial sections taken on the lines 4—4 and 5—5 respectively of Fig. 1.

Referring to the drawing more in detail, the invention is shown as applied to a vessel 10, 35 which may comprise a flash chamber or the like in an oil cracking plant. Such vessels are of large dimensions and comparatively heavy. For supporting the vessel 10 there are provided a plurality of legs 11, preferably four in number, 40 each of which comprises a tubular member 12, such as a steel rod, to which a pair of cross plates 13 and 14 are secured, as by welding. The cross plate 13 may be provided with an aperture 15 through which the tubular member 12 extends. 45 The cross plate 14 is preferably butt-welded to the end of the tubular member 12. The cross plates 13 and 14 are themselves butt-welded to the outside surface of the vessel 10. Compression members such as triangular bracing plates 16 are secured by butt-welding to the cross plate 14 and to the outer surface of the vessel 10. A cover plate 17 is secured between the bracing plates 16 and is welded thereto. Side plates 18 50 extend between the cross plates 13 and 14 from

the tubular member 12 to the outer surface of the vessel 10 to enclose the assembly and to increase the strength thereof.

All of the joints of the various plates to the tubular member 12 and to the wall of the vessel 10 are preferably butt-welded so as to form a rigid mounting for the legs. The various plates form, in effect, an open box or truss, the edges of which may readily be secured to the vessel and which is adapted to support the weight of the 10 vessel without distortion. The vessel may be constructed at the factory with the legs 11 attached thereto, so that the amount of construction work in the field is reduced to a minimum.

A base 20, of any suitable material such as 15 concrete, may be formed with recesses adapted to receive the legs 11. The tubular members 12 enter said recesses and are secured therein by concrete. The tubular members 12 are also provided with an outer coating 21 of concrete, which 20 strengthens the assembly and protects the members from injury. This coating 21 may be applied after the vessel has been erected, by positioning a thin shell 22, such as steel, around the tubular member 12 and leaving a suitable opening 25 through which the concrete can be poured. The shell 22 may remain in position permanently to protect the concrete from damage.

Although a specific form of supporting leg has 30 been disclosed for purposes of illustration, it is obvious that various changes and modifications may be made therein by a person skilled in the art without departing from the scope of the invention. The supporting legs are particularly suitable for the various heavy towers and vessels 35 used in an oil cracking plant. It is to be understood, however, that the use of these supporting legs is not limited to such apparatus. The scope of the invention is only to be limited in accordance with the following claim, when interpreted 40 in view of the prior art.

What is claimed is:

A support for a heavy metal vessel comprising a plurality of supporting legs and a butt-welded truss securing each leg to said vessel, each of 45 said trusses comprising a horizontal plate butt-welded to the top of a leg and having an edge engaging and butt-welded to the surface of said vessel, a second horizontal plate having an opening through which said leg extends, said second 50 plate being horizontally spaced below said first plate and likewise being butt-welded both to said leg and to said vessel, side plates closing the area between said horizontal plates and said vessel, 55 said side plates being butt-welded to said vessel

and to said first plates, a pair of triangular plates above the upper transverse plates and in approximately the planes of said side plates, said triangular plates being butt-welded to the upper transverse plate and to said vessel and an inclined plate butt-welded to said triangular plates

and to said vessel to close the area between said triangular plates, said plates forming, in effect, an open box-like truss which is resistant to deformation and forms a rigid support for said vessel.

RALPH M. PARSONS.
